UNITED STATES PATENT OFFICE.

WALTER F. KOKEN, OF ST. LOUIS, MISSOURI.

BARBER'S CHAIR.

Application filed March 3, 1923. Serial No. 622,518.

To all whom it may concern:

Be it known that I, WALTER F. KOKEN, a citizen of the United States, residing at St. Louis, Missouri, have invented a certain new and useful Improvement in Barbers' Chairs, of which the following is a full, clear, and exact description, such as will enable others skilled in the art to which it appertains to make and use the same.

This invention relates to chairs of the kind that are used by barbers, dentists and other specialists for supporting a person on whom the specialist is operating, and particularly to chairs of the type that comprise a seat that can be adjusted vertically and a back that can be swung upwardly and downwardly relatively to the seat so as to arrange the back either in an inclined position, commonly referred to as the "reclined" position of the back, or in an upright position.

The main object of my present invention is to provide a chair of the general type referred to which is so constructed that the adjustment of the various parts of the chair can be effected by one hand of the operator in charge of the chair, thereby overcoming the necessity of requiring the operator to manually release a retaining device with one hand and use the other hand to move the part of the chair that is to be adjusted.

Another object is to provide a chair of the general type referred to that is equipped with an electrically-operated means of novel construction for raising the seat of the chair and for moving the back relatively to the seat to change the adjustment of the back.

And still another object is to provide a barbers' chair or the like that is equipped with an hydro-electric mechanism for adjusting the seat and adjusting the back, and a governing means for said mechanism constructed in such a manner that only one hand of the operator is required to raise or lower the seat or to arrange the back in an upright position or in an inclined position. Other objects and desirable features of my invention will be hereinafter pointed out.

To this end I have devised a chair that comprises a vertically-movable seat that is adapted to be raised and lowered, and adjustable back that is adapted to be arranged in an upright position or in an inclined position, mechanism for effecting the vertical movement of the seat and for moving the back relatively to the seat to change the

position of the back, an electric motor for operating said mechanism, and a governing means for said mechanism and motor constructed in such a way that it can be actuated by one hand of the operator in charge of the chair, thus leaving the other hand of the operator free to manipulate an instrument that is being used in the work in which the operator is engaged. The mechanism that I prefer to use for moving the seat vertically and for moving the back relatively to the seat consists of two separate and distinct cylinders equipped with pistons, and a motor-driven pump for circulating a non-compressible liquid that acts on said pistons, and the governing means that I have herein illustrated for controlling the operation of said mechanism consists of a distributing valve for governing the circulation of the liquid that acts on the pistons and a switch for governing the motor circuit. I wish it to be understood, however, that my broad ideaa contemplates the use of any suitable mechanism for moving the seat vertically and for moving the back relatively to the seat and any suitable governing means for said mechanism, and further, that when said mechanism comprises pistons any suitable operating medium such as a circulating liquid or a fluid under pressure can be used to operate said pistons.

I am aware of the fact that barbers' chairs and the like have heretofore been devised that were equipped with an electrically-operated means for effecting the vertical movement of the seat of the chair, but such prior chairs did not comprise a means for moving the back relatively to the seat to change the adjustment of the back. While such chairs are an improvement on a chair of the kind in which the operator has to manually operate a device to raise the seat of the chair, they do not overcome the necessity of the operator laying down his instrument and manually moving the back each time the position of the back is changed. The time lost by the operator in laying down the instrument being used on the occupant of the chair and manually raising or lowering the back each time the position of the back is changed reduces the amount of work that a barber can do in a given time, and moreover, adds considerable to the fatigue of the barber. My invention overcomes this objectionable characteristic of the conventional barbers' chair and of electrically-operated bar-

bers' chairs that have heretofore been devised, due to the fact that it contemplates equipping a barbers' chair or the like with a means controlled by one hand of the 5 barber for effecting the vertical adjustment of the seat and for moving the back relatively to the seat to change the adjustment of the back.

Figure 1 of the drawings is a vertical 10 sectional view of a portion of my improved chair, showing the seat frame, the stem which carries said frame and the vertically-disposed socket or cylinder in which said stem is reciprocatingly mounted.

Figure 2 is a detail view, taken on the 15 line 2—2 of Figure 1, looking in the direction indicated by the arrows.

Figure 3 is a vertical sectional view of the 20 distributing valve.

Figure 4 is a detail sectional view, taken on the line 4—4 of Figure 3, looking in the direction indicated by the arrows.

Figures 5 to 9, inclusive, are diagrammatic views, illustrating the various positions of the shaft that actuates the crank of the stem locking means, the controlling element of the distributing valve and the shiftable circuit closing device of the switch in the motor circuit.

Figure 9^a is a perspective view of a portion 30 of the casing of the distributing valve.

Figure 9^b is a perspective view of the controlling element of the distributing valve.

Figure 10 is a diagrammatic view, showing 35 how the motor and the switch in the motor circuit are electrically connected with the electric supply circuit.

Figures 11 and 12 are diagrammatic views, illustrating how the distributing 40 valve controls the circulation of the operating medium in effecting the adjustment of the back of the chair.

Figures 13 and 14 are diagrammatic views, illustrating how the distributing valve controls the circulation of the operating medium in raising and lowering the seat of the 45 chair, the valve casing being shown in top plan and the socket and stem in vertical section; and

Figures 15 and 16 are side elevational 50 views of the chair, showing the back arranged in an upright position and in an inclined position.

In the accompanying drawings I have illustrated 55 my invention embodied in a barbers' chair of the type that comprises a vertically-adjustable seat A, an adjustable back B that can be arranged in an upright position, as shown in Figure 15, or an inclined 60 position, as shown in Figure 16, an apron C and arms D connected with the back B in such a manner that they will move in unison with the back, a supporting base or standard E provided with a vertically-disposed socket or cylinder F and a piston or

stem G in said socket connected at its upper end to the seat frame H of the chair. The seat A of the chair is raised by pumping a non-compressible liquid such as oil into the lower end of the socket F in the standard, so as to force the stem G upwardly, and said seat is lowered by permitting the liquid to escape from the socket F. Any suitable kind of

pump can be used for circulating the liquid that actuates the stem G of the chair, but I 70 prefer to use a rotary pump I arranged in the seat frame of the chair and operate said pump by an electric motor J which is also arranged in the seat frame of the chair. The means herein illustrated for moving the 75 back of the chair relatively to the seat consists of a horizontally-disposed cylinder K arranged in the seat frame and provided with a piston that is operatively connected by a piston rod 1 and a system of links 2, 80 3 and 4 to the apron C of the chair in such a way that the outward movement of said piston causes the back, arms and apron of the chair to move into the position shown in Figure 16 and the inward movement of said 85 piston causes said back, arms and apron to move into the position shown in Figure 15. When it is desired to recline the back of the chair the operator actuates a device which sets the pump I in operation and also causes 90 the operating medium to be supplied to the cylinder K in such a way that the piston of said cylinder will move outwardly, and when it is desired to restore the back to its 95 normal upright position, the operator actuates said device so as to cause the operating medium to move the piston in the cylinder K in the opposite direction. The vertical 100 movement of the seat of the chair can also be effected by operating the device just referred to so as to cause the operating medium to be admitted to or exhausted from 105 the cylinder F in the standard of the chair in which the stem G reciprocates.

Controlling means.

The means that I have herein illustrated for controlling the circulation of the operating medium consists of a distributing valve provided with a controlling element that is 110 adapted to be moved into one position to cause the seat to move upwardly, into another position to cause the seat to move downwardly, into another position to cause the back to swing downwardly into an inclined or reclined position, into another position to cause the back to swing upwardly into an upright position and into another position to hold the seat at a certain level and prevent the back from swinging in either direction relatively to the seat. The motor J which actuates the pump I is controlled by a switch which is preferably combined with said distributing valve in such a way that when the controlling element of 115

said valve is moved to cause the seat to move upwardly or to cause the back to swing upwardly or downwardly relatively to the seat, the motor will become operative, 5 and when the controlling element of said valve is moved to bring the seat to rest or to bring the back to rest, the motor will stop automatically, thereby enabling the adjustment of the various parts of the chair 10 to be governed by a means that can be actuated by one hand of the operator. In chairs of the type to which my invention relates the stem G is usually mounted in the socket F in such a way that it can turn in said 15 socket so as to permit the seat frame of the chair to be revolved, and a clamping device is provided for holding said stem against rotary movement. The chair herein illustrated is provided with a stem holding device or clamping device of the character referred to, and said device is combined with the controlling means of the chair, previously described, in such a way that the stem locking device will be rendered 20 operative automatically whenever the controlling element of the distributing valve is moved to effect the adjustment of the seat or back of the chair and will be rendered operative automatically whenever 25 said controlling element is moved to cut off the circulation of the operating medium.

Distributing valve.

Any suitable kind of distributing valve 30 can be used for controlling the circulation of the operating medium, but I prefer to use a distributing valve of the kind herein illustrated which consists of a casing, designated as an entirety by the reference character L and equipped with circulating passageways, and an oscillating or rotatable controlling element M provided with ports and ducts that are adapted to be brought into registration with the passageways in 35 said casing so as to permit the operating medium to pass to and from the cylinder F that forms part of the means for moving the seat vertically and to and from the cylinder K that forms part of the means for moving 40 the back relatively to the seat.

As shown in Figures 11 and 12, the casing of the distributing valve comprises a portion 10 equipped with passageways 5 and 5^a that lead to the opposite ends of the cylinder 55 K, as shown in broken lines in Figure 9^a, a web 6, a closed distributing chamber 7 arranged at one side of the web 6 and a sump or hollow space 8 on the other side of the web 6 that discharges into a hollow space in 60 the stem G, said hollow stem G serving as a reservoir for the liquid that is used to actuate the parts which effect the movement of the seat and the back of the chair. The controlling element M of the distributing 65 valve is disk-shaped and is arranged in the

distributing chamber 7 of the valve casing in such a way that one side of same bears snugly against the web 6 of the valve casing, said controlling element being rigidly connected to a governing shaft or operating 70 shaft N and being held in snug engagement with the web 6 of the valve casing by means of a spring or other suitable device 9. The controlling element M is provided with two ports 11 and 12 that extend transversely 75 through the said element, and two ducts or grooves 13 and 14 that are formed on the inner face of said controlling element which bears against the web 6 of the valve casing, the duct 13 consisting of a short straight 80 groove and the duct 14 consisting of a substantially angle-shaped groove. The web 6 of the valve casing L that separates the distributing chamber 7 from the sump 8 is provided with two ports 15 and 15^a that communicate with the passageways 5 and 5^a in the valve casing that lead to the opposite ends of the cylinder K, two ports 16 and 17 that discharge into the sump 8 of the valve 85 casing and a port 18 that leads to a pipe or conduit 19 in the stem G whose lower end terminates in the end face of said stem or projects downwardly below the same so as to communicate with the cylinder or socket F in the standard of the chair. The pump I 90 is arranged at one side of the casing of the distributing valve and is provided with an inlet pipe or conduit 20 that extends downwardly into the stem G and terminates at a point above the lower end of said stem, as 95 shown in Figure 1, thereby establishing direct communication between the housing of the pump and the hollow stem of the chair that forms a reservoir for the liquid operating medium. The discharge from the pump I 100 communicates with a passageway in the casing of the distributing valve that leads into the distributing chamber 7 of said valve casing, as indicated by the arrows in Figure 11 and 12.

When it is desired to raise the seat A of the chair the shaft N is turned into the position shown in Figure 5 so as to set the pump I in operation and cause the controlling element M of the distributing valve to 105 be arranged in such a position that the port 12 therein will register with the port 18 in the web of the valve casing. The pump I will then cause the liquid in the hollow stem G to circulate upwardly through the inlet pipe 20 of the pump into the distributing chamber 7 of the valve casing and then pass from said distributing chamber through the ports 12 and 18 into the pipe 19 down 110 through which it circulates into the socket F, as indicated by the arrows in Figure 14, thus causing the stem and seat frame to move upwardly. If it is desired to stop the seat at a point intermediate the high and 115 low level of the seat, the shaft N is turned 120

so as to stop the pump and cause the controlling element M of the distributing valve to move into a position to close the port 18, thereby cutting off communication between the distributing chamber of the valve casing and the pipe 19 and trapping the liquid in the socket or cylinder F. In order to prevent the mechanism of the chair from being damaged or injured in the event the operator fails to stop the pump and turn the controlling element M of the distributing valve into such a position as to trap the liquid in the socket F, after the seat frame has reached its extreme upper position, said socket F is provided with a by-pass 21, as shown in Figure 14, that establishes communication between the socket or cylinder F and the interior of the hollow stem G when the stem reaches the end of its upward stroke. Consequently, if the pump is allowed to continue in operation after the seat has reached its extreme upper position, the liquid will continue to circulate from the socket F up through the by-pass 21, upwardly through the pipe 20 into the distributing chamber 7 and from said distributing chamber back through the pipe 19 to the socket F, as indicated by the arrow in Figure 14.

To lower the seat the operator turns the shaft N into the position shown in Figure 8, so as to cause the angle-shaped duct 14 in the controlling element M of the distributing valve to register with the ports 17 and 18 in the web 6 of the valve casing, thereby establishing communication between the pipe 19 and the sump 8 of the valve casing and causing the liquid in the socket F to be forced upwardly through the pipe 19 and be discharged into the hollow stem G, as indicated by the arrows in Figure 13, by the downward pressure which the stem G exerts on the liquid in the socket F, the stem continuing to move downwardly by gravity until it reaches the end of its downward stroke or until the controlling element M of the distributing valve is moved to cut off communication between the ports 17 and 18 in the web of the valve casing.

If it is desired to move the back B of the chair from its upright position shown in Figure 15 into its inclined position shown in Figure 16, the shaft N is turned into the position shown in Figure 6, so as to start the pump and cause the controlling element M of the valve to be arranged in such a position that the port 11 therein will register with the port 15 in the web 6 of the valve casing and the angle-shaped duct 14 in said controlling element will establish communication between the ports 15^a and 16 in said web. The pump then causes the liquid in the hollow stem G to circulate upwardly into the distributing chamber 7, and thence through the ports 11 and 15 into the left hand end of the cylinder K, looking at Figure 11, thus causing the piston in said cylinder to move outwardly and the liquid in front of said piston to be discharged through the port 15^a, duct 14 and port 16 into the sump 8 of the valve casing, as indicated by the arrows in Figure 11, the liquid, after entering the sump of the valve casing, escaping from same down into the hollow stem G. When the controlling element M of the distributing valve is turned into a position to close the port 15 and cut off communication between the ports 15^a and 16 in the web 6 of the valve casing, the pump will stop and the back of the chair will come to rest and be retained in its adjusted position, due to the fact that the liquid is trapped in the cylinder K on opposite sides of the piston in said cylinder. If the operator fails to stop the pump and change the position of the controlling element of the distributing valve after the back has reached its fully inclined position, the liquid will continue to circulate from the distributing chamber of the valve casing through the left hand end portion of the cylinder K and then escape from said cylinder back into the sump 8 through a lateral discharge outlet 22 in the cylinder which is uncovered when the piston is at the end of its stroke in this direction, thereby preventing damage or injury to the mechanism in the event the operator fails to stop the pump after the back has reached its fully inclined position.

To raise the back from its reclined position into its upright position the shaft N is turned into the position shown in Figure 7, so as to start the pump and arrange the controlling element M of the valve in such a position that the port 11 therein registers with the port 15^a in the web 6 of the valve casing, and the straight duct 13 in said controlling element establishes communication between the ports 16 and 15 in said web, the pump causing the liquid to circulate from the distributing chamber 7 into the right hand end of the cylinder K and the liquid in the opposite end portion of said cylinder to escape from same through the port 15, duct 13 and port 16 back into the sump 8, as indicated by the arrows in Figure 12. If the operator fails to stop the motor after the back has reached its vertical position, the liquid that is admitted to the right hand end portion of the cylinder K will escape through the lateral discharge outlet 22 leading from said cylinder, and thus prevent damage or injury to the mechanism, said outlet port 22 being so arranged with relation to the piston that it is open when the piston is at the end of its stroke in either direction, but is covered by the piston at all other times. From the foregoing it will be understood that in a chair of the construction above described

it is not necessary to reverse the motor J to change the direction of movement of the seat or to change the direction of movement of the back. On the contrary, the armature shaft of the motor always revolves in the same direction and the change in the direction of movement of the seat and of the back is effected by changing the direction of circulation of the operating medium.

10

Switch.

As previously stated, the switch that governs the motor circuit is combined with the distributing valve in such a way that the motor will be started and stopped automatically when the controlling element M of the distributing valve is moved into certain positions. The switch that I prefer to use for controlling the motor circuit comprises two stationary contacts 23, arranged in the motor circuit, and a shiftable circuit closing device 24 that is adapted to snap into engagement with said contacts in three different positions of the controlling element M. As shown in Figure 1, the operating shaft N of the distributing valve projects outwardly through the seat frame H of the chair and is provided at its outer end with a governing handle O that has a hollow hub O' which is rigidly connected to the shaft N. A stationary insulator 25 that is rigidly connected to the seat frame of the chair and which projects into said hub O' carries the contacts 23. The circuit closing device 24 that co-operates with said contacts consists of a bar of conducting material set in a piece of insulation 26 carried by a pivotally mounted device 27 connected to the inside of the hub of the handle O, as shown in Figure 2. Said device 27 is acted upon by a spring 28 that normally tends to move the circuit closing device 24 into engagement with the contacts 23 and the handle O is provided with a finger piece 29 that is connected by a link 30 with the device 27, so as to move said device 27 in a direction to disengage the circuit closing device 24 from the contacts 23. The insulator 25 is provided at its outer end with a disk-shaped portion 31 on which the pivotally mounted device 27 rides when the handle O is moved to change the position of the controlling element of the distributing valve, and said disk-shaped portion is provided with four notches 31^a shown in Figures 5 to 9 arranged in such a way that when the handle O is set in a position to cause the seat to move upwardly the device 27 will snap into one of said notches, thereby causing the circuit closing device 24 to engage the contacts 23 to close the motor circuit, whereupon the pump will be set in operation. Likewise, when the handle O is set in position to move the back downwardly, or set in position to move

the back upwardly, the other notches 31^a in the disk-shaped portion 31 of the insulator 25 permit the spring 28 to move the circuit closing device into engagement with the contacts 23, so as to close the motor circuit. As soon as the operator depresses the finger piece 29 preparatory to changing the position of the controlling element of the distributing valve the link 30 will move the circuit closing device 24 out of engagement with the contacts 23, thus opening the motor circuit and rendering the pump inoperative. When the handle O is moved into position to cause the seat to move downwardly, the pivotally mounted device 27 on said handle snaps into the fourth notch in the disk-shaped portion 31 of the insulator 25, and thus indicates to the operator that the handle is in proper position to lower the seat. In this position of the handle the circuit closing device 24 will not engage the contacts 23, as it is not necessary for the pump to be in operation when the seat is being lowered. When the handle O is set in position to cause the seat and back to remain at rest, the unnotched part of the disk-shaped portion 31 of the insulator 25 will hold the circuit closing device 24 out of engagement with the contacts 23.

Stem locking device.

As previously stated, the chair is equipped with means for locking the stem G so as to prevent the seat frame of the chair from being revolved. In the form of my invention herein illustrated said means consists of a clamping device or shoe P mounted in the stem G of the chair in such a way that it is capable of being moved into engagement with the inner side of the socket F, as shown in Figure 1, an actuating device or expanding device Q for moving said shoe outwardly into engagement with the side wall of the socket F, thus causing the stem to be clamped and held against rotary movement, an operating rod 32 for the expanding device Q that projects upwardly through the stem G, and a crank R on the operating shaft N to which the governing handle O is connected, constructed in such a way that when said handle O is set in the position shown in Figure 9 to hold the seat and back at rest, said crank R will exert pressure on the rod 32 in a direction to render the stem clamping device P operative, and when said handle O is set in any of its various other positions, the crank R will permit the rod 32 and expanding device Q to move downwardly far enough to release the clamping pressure of the shoe P on the socket, and thus permit the stem to be turned.

Electric conductors.

In order that the chair will not have

numerous loose wires or flexible conductors that might interfere with the raising or lowering of the seat or revolving the seat, or interfere with the movement of the back 5 relatively to the seat, I attach a collector ring insulator S to the underside of the seat frame H, as shown in Figure 1, and combine the collector rings on said insulator with vertically-disposed conductor bars T that 10 are reciprocatingly mounted in the standard of the chair and arranged in sliding engagement with contacts U in the standard to which electric supply wires W are connected, the exposed portions of the conductor bars T being covered with insulating material and each of said bars being provided at its upper end with a shoe or brush 15 33 equipped with a notch that receives one of the collector rings on the insulator S. 20 One of the collector rings 34 is connected by a wire 35 with the motor and the other collector ring 36 is connected by a wire 37 with one of the contacts 23, the other contact being connected by a wire 35^a with the motor. 25 As shown in Figure 1, said various wires are arranged inside of the seat frame of the chair. The conductor bars T are mounted in the standard of the chair and are combined with the collector rings in 30 such a way that they will move vertically in said standard when the seat frame H is raised and lowered and the shoes or brushes 33 at the upper end of said conductor bars are combined with the collector rings on 35 the insulator S in such a way that the seat frame can be revolved without disturbing the electrical connection between the supply wires W and the contacts 23 of the switch in the motor circuit. 40 Having thus described my invention, what I claim as new and desire to secure by Letters Patent is:

1. A chair, comprising a seat, a back, a piston device for adjusting the seat vertically, a piston device for moving the back relatively to the seat, a pump for circulating an operating medium that acts on said piston device, a motor for driving said pump and a manually-operable means for starting 45 and stopping said motor and for controlling the circulation of the operating medium that acts on both of said piston devices. 50

2. A chair provided with a seat, a back, an hydro-electric mechanism for moving the seat vertically and for moving the back relatively to the seat, and a controlling means for said mechanism that causes the electric portion of said mechanism to be rendered operative automatically when said 55 controlling means is actuated to cause the seat to move upwardly or the back to move relatively to the seat and to remain inactive when said controlling means is actuated to cause the seat to move downwardly or the 60 back and seat to remain at rest. 65

3. A chair, comprising a seat, a back, an hydraulic means for moving the seat vertically and for moving the back relatively to the seat, an electrically-operated means for circulating a liquid that causes said hydraulic means to operate, and a controlling mechanism consisting of a governing means for said liquid and an electric switch combined in such a way that said electrically-operated means will be rendered operative 70 and inoperative automatically in certain positions of the governing means for said liquid. 75

4. A chair, comprising a seat, a back, a vertically-adjustable stem that carries the seat, a socket in which said stem reciprocates, a cylinder equipped with a piston for moving the back relatively to the seat, a pump for circulating an operating medium, and means for causing the operating medium to be admitted to said socket so as to raise the stem or admitted to either end of said cylinder so as to raise or lower the back. 80

5. A chair, comprising a seat, a back, a vertically-adjustable stem that carries the seat, a socket in which said stem reciprocates, a cylinder equipped with a piston for moving the back relatively to the seat, a pump for circulating an operating medium, and means for admitting and exhausting the operating medium to and from said socket to raise and lower the seat and for admitting the operating medium to and from the opposite ends of said cylinder so as to raise and lower the back. 90

6. A chair, comprising a seat, a back, a stem that carries said seat and is provided with a hollow space that serves as a liquid reservoir, a socket in which said stem is reciprocatingly mounted, a cylinder provided with a piston for moving the back relatively to the seat, a pump for circulating an operating liquid, said pump having an intake that communicates with said liquid reservoir, a distributing valve comprising a casting having a distributing chamber that communicates with the discharge of said pump and a sump that communicates with said liquid reservoir, and a controlling element for governing the escape of the liquid from said distributing chamber to said cylinders and for governing the escape of the liquid from said cylinders to said sump. 100

7. A chair, comprising a seat, a back, a stem that carries said seat, a liquid reservoir in said stem, a socket in which said stem is reciprocatingly mounted, a cylinder provided with a piston for moving the back relatively to the seat to raise and lower the back, a motor-driven pump for circulating a liquid operating medium, provided with an intake pipe that communicates with said liquid reservoir, a distributing valve having a distributing chamber into which the liquid is discharged from said pump and 110 115 120 125 130

equipped with a sump that communicates with said liquid reservoir, and a controlling element that is adapted to be set in one position to hold the seat and back at rest, in a different position to cause the seat to move upwardly, in a different position to cause the seat to move downwardly, in a different position to cause the back to tilt downwardly and in a different position to cause the back to swing upwardly.

8. A chair, comprising a seat, a back, an hydro-electric mechanism, comprising an electric motor and a pump for circulating a liquid that causes the seat to move vertically and causes the back to move relatively to the seat, and means for permitting said liquid to circulate freely, thus preventing said mechanism from being injured or damaged in the event said mechanism is permitted to continue in operation after the seat has reached its extreme elevated position or after the back has reached its limit of movement in either direction.

9. A chair, comprising a seat, a back, a vertically-movable stem that carries said seat, a cylinder provided with a piston for moving the back relatively to the seat, a motor-driven pump for circulating an oper-

ating medium that is used to raise the stem and to actuate said piston, a device for holding said stem against rotary movement, and a controlling means for actuating said stem holding device, for governing the circulation of said operating medium and for controlling the circuit that energizes the motor of said pump.

10. A chair, comprising a seat, a back, a hollow stem that carries said seat, a socket in which said stem is reciprocatingly mounted, a cylinder provided with a piston for moving the back relatively to the seat, a motor-driven pump for circulating an operating medium, a distributing valve provided with a controlling element for the operating medium, a device for holding said stem against rotary movement, and means for causing said stem holding device to be rendered inoperative automatically when the controlling element of said valve is moved to effect the adjustment of the seat or the back of the chair and for rendering said stem holding device operative automatically when said controlling element is moved into a position to hold the back and seat at rest.

WALTER F. KOKEN.
